UNITED STATES PATENT OFFICE.

JOHN K. STEWART, OF CHICAGO, ILLINOIS, ASSIGNOR TO STEWART MANUFACTURING COMPANY, OF CHICAGO, ILLINOIS, A CORPORATION OF ILLINOIS.

PENCIL-SHARPENER.

1,160,091.

Specification of Letters Patent.

Patented Nov. 9, 1915.

Application filed July 6, 1914. Serial No. 849,104.

To all whom it may concern:

Be it known that I, JOHN K. STEWART, a citizen of the United States, residing at Chicago, in the county of Cook and State 5 of Illinois, have invented new and useful Improvements in Pencil-Sharpener, of which the following is a specification, reference being had to the accompanying drawings, forming a part thereof.

10 The purpose of this invention is to provide an improved device for sharpening pencils.

It consists of the features and elements described and shown in the drawings as indicated in the claims.

15 In the drawings:—Figure 1 is a side elevation of a device embodying this invention, having the case broken away to show the interior parts. Fig. 2 is a section at the line 2—2 on Fig. 4. Fig. 3 is a section at the line 20 3—3 on Fig. 4. Fig. 4 is a section at the line, 4—4, on Fig. 2. Fig. 5 is a section at the line, 5—5, on Fig. 4.

The device shown in the drawings comprises a casing, A, which is preferably die-cast and integral. This casing comprises as an integral part thereof an elongated shaft bearing, 3, protruding outwardly, and a fixed internal gear or annular internally 25 toothed rack, 4, formed in a hollowed boss or flange, B², projecting inward in the casing co-axial with the outwardly protruding shaft bearing, 3. Journaled in the bearing, 3, is a rotating member, B, having an elongated spindle, 5, for journaling in said shaft bearing and projecting there-beyond to receive an operating handle, 6, and having a circular base, B¹, around the inner end of the spindle, which base enters within 30 and closes the cavity of the inwardly-projecting boss, B², whose inner end constitutes the internally-toothed rack, 4, above mentioned. The cavities thus inclosed may serve as a grease pocket for lubrication of 35 the spindle the circular base closing said pocket, serving to prevent the grease from escaping so as to soil the pencil or mingle with the shavings. The rotating member is of such dimension as to extend entirely 40 through the casing and there-beyond at the end opposite the spindle in the form of a hollow boss, 7, whose axial cavity constitutes a pencil guide. This pencil guide protrudes at the center of the circular head, 8, 45 of the rotating member, which head guides 50 and closes a circular aperture in the wall of the casing, A, at the side opposite that at which the internal annular rack, 4, is situated. At the portion of the rotating member which extends between the front 55 and rear walls of the casing,—that is, from the face of the spindle, 5, to the inner face of the head, 8,—it is provided with diametrically opposite recesses, 10, 10, which accommodate rotating cutters, 11, 11, each having at its end toward the spindle a bevel gear, 12, said bevel gears meshing with the internal annular rack, 4. These cutters are each axially apertured and journaled for rotation upon a shaft, 13, which is inserted 60 through the head, 8, on the outer side thereof, having the opposite end threaded and screwed into the rotating member at the shoulder which defines the inner end of the recess in which the rotating cutter is accommodated. The two cutters are each cylindrical with spiral cutting edges, 15, each of said cutting edges extending continuously from one end to the other of the operating portion of the length of the cutter. 65 They are mounted in the rotating member at an acute angle to each other which is bisected by a plane through the axis of rotation of said member, said cutters converging from outer to inner end, that is, from 70 the end at which the pencil guide is situated to the end having the pinions for meshing with the internal rack. The recesses formed in the rotating member to accommodate the two cutters thus converging toward the 75 pinions, cut into each other as they approach said end toward which they converge, leaving standing between the cutters a tapered portion of the substance of the 80 rotating member at the inner end of the pencil guide-way; and said pencil guide is bored tapering at said inner end, forming a tapering seat between the two cutters at their diverging ends. The conical bore for 85 this tapering seat cuts into the portion of the rotating member left standing between the recesses for the rotating cutters, so that 90 said tapering seat opens into said recesses at the opposite sides, with the result that there is left standing at opposite sides of the 95 tapering bore between the two cutters two 100 conically concave seats, 17, for the end of the pencil and in which the latter seats as 105 it is sharpened to tapering form by the 110 operation of the cutters rotated by their

pinions engaging the annular rack, while they receive planetary motion about the pencil axis by rotation of said rotating member about the said axis.

5 The two cutters are mounted in the rotating member so that their cutting edges just clear each other at their proximate ends, and they are reduced in diameter beyond that point forming annular shoulders, 18, 10 between which there is mounted on the carrier a stop bar, 20, which extends across the axis of the rotating member and of the pencil to be sharpened, and forms a stop for the point of the pencil so that when the pencil has been sharpened to the finest point for which the device is adapted, that point rests against said bar, and if the pencil is still farther pushed in by the operator the lead of the reduced point will crumble under the 20 pressure as fast as the pencil is further sharpened or cut away, and the pencil can be forced in only as fast as the pointed lead crumbles.

The case is cut away at one side of the 25 lower end forming an opening, 22, to receive a slide drawer, 23, which stands below the cutters and receives the pencil trimmings.

I claim:-

30 1. A pencil sharpener comprising a casing having a shaft-bearing extending outwardly from one end thereof and having at the same end an annular inwardly-projecting flange concentric with said bearing and 35 forming a chamber about the inner end thereof; a rotating member having a spindle journaled in said shaft-bearing, and a circular base which closes the inner end of said chamber; cutters journaled for rotation in 40 said rotating member between the end having the spindle and the opposite end thereof, said cutters being provided with means for engaging said annular flange for rotation of the cutters in the rotating member 45 when the latter is rotated in the casing.

2. A pencil sharpener comprising a casing having a shaft-bearing extending outwardly from one end thereof; a rotating member having a spindle journaled in said 50 shaft-bearing; diverging cutters journaled in said rotating member between the end having the spindle and the opposite end thereof, for rotation both in and with said rotating member, said member having at 55 the end opposite the spindle a circular head whose diameter is at least as great as that of the path of rotation of said cutters about

the spindle axis at the point of greatest diameter of said path, and the case having at the end opposite said shaft bearing a circular opening which said head fits and closes when the rotating member is in operating position in the case.

3. A pencil sharpener comprising a casing having a shaft-bearing extending outwardly from one end thereof and having at the same end an annular inwardly-projecting hollowed boss having its cavity concentric with said bearing; a rotating member having a spindle journaled in said shaft-bearing, and cutters journaled for rotation in said rotating member between the end having the spindle and the opposite end thereof, the opposite end of the casing having a circular aperture through which said rotating member and the cutters thereon may be entered bodily for inserting the spindle in the spindle bearing to operating position, said rotating member having a circular head opposite the end having the spindle which fits and closes said circular opening, the rotating cutters being provided with means for engaging the hollowed boss for rotation of the cutters in the rotating member when the latter is rotated in the casing, the spindle being long enough to extend entirely through, said outwardly-extended bearing for the same, and to project thereto, and a handle secured thereto at the protruding end, and locking the rotating member against endwise displacement in the casing.

4. A pencil sharpener comprising a casing having a shaft-bearing extending outwardly from one end thereof, and having at the same end an annular inwardly-projecting hollowed boss concentric with said bearing and forming a chamber about the inner end thereof; a rotating member having a spindle journaled in said shaft-bearing, and bearings for rotary cutters to be mounted for rotation both in and with said rotary member, said rotary member having between the base of the spindle and said cutter bearings a circular base which fits and closes the inner end of the chamber formed by said hollowed boss.

In testimony whereof, I have hereunto set my hand at Chicago, Illinois, this 1st day of July, 1914.

JOHN K. STEWART.
